Tar & Petroleum Process Company, Chicago,
Ill., a corporation of Illinois

Application April 20, 1940, Serial No. 330,655

6 Claims. (Cl. 202—102)

The present invention relates to improvements in ovens.

More particularly the present invention relates to improvements in the type of coke oven construction described and claimed in Patent No. 2,148,108 to Maurice D. Curran, dated February 21, 1934. Said Patent No. 2,148,108 relates to the general subject matter of the Knowles Patent No. 1,745,996, granted February 4, 1930, having to do with a sole-fired coke oven heated by a plurality of independent sole combustion flues arranged beneath the sole of the oven. Said Curran Patent No. 2,148,108 contemplated means for accomplishing uniformity of flue heating.

An object of the present invention is to provide a construction in which the sole combustion flues may be supplied with either blast furnace gas, producer gas, coke oven gas, or oil gas, said types of gas to be used either simultaneously or alternatively.

A further object of the present invention is to provide a construction whereby oil gas may be efficiently supplied to a coke oven at the point where it is most needed and can be utilized to the best advantage.

A further object is to provide an oven wherein oil can be used as the sole fuel for oven firing, or used simultaneously with gas, either fuel supplementing the other.

Further objects will appear as the description proceeds.

The one figure of the drawing is a cross-sectional view indicating more or less diagrammatically one embodiment of the present invention.

The numeral 1 indicates the floor or sole of a coke oven, and the numeral 2 indicates the roof thereof. Said roof may be provided with means for charging coal into the oven. The numeral 4 indicates an opening through which gas and by-products may be taken off. Each front of the oven chamber may be provided with a door (not illustrated).

Disposed below the floor 1 are a plurality of flues 7 extending longitudinally of the oven. Said flues may be separated by walls (not illustrated) upstanding from the horizontal wall 8, which walls define the bottom boundary of the flues 7. As illustrated in the drawing, said wall 8 is formed to provide apertures 9—9 adjacent to the end walls of the oven whereby to provide communication from the flues 7 to the space below the wall 8. Projecting downwardly from the wall 8 is the medial wall 10 dividing the space below the horizontal wall 8 into two regenera-

tors. Projecting from each end wall of the oven is a baffle wall 11, which baffle walls are shaped to provide apertures 12—12 adjacent to the medial wall 10. Each of said baffle walls 11—11 provides a U-shaped passageway, or hairpin passageway, indicated by the numeral 13, from a region adjacent to an end wall of the oven to a region adjacent to the medial wall 10 back to the region of the corresponding aperture 9.

10 Connecting with the passageways 13—13 of the regenerators at the two ends of the oven are downtakes 14—14 leading to the waste gas tunnels 15—15.

According to the illustrated embodiment of 15 the present invention, the oven is provided with a plurality of passageways 16—16 extending from the two ends of the oven to regions adjacent to the medial wall 10. Said passageways 16—16 communicate with the atmosphere at the 20 two ends of the oven, and adjacent to the middle of the oven communicate with air downtakes 17—17 which lead to the two hot air tunnels 18—18. Each of the tunnels 18 communicates with a pipe 20, which, through a fan box 21 (equipped with the necessary valve), leads to an air header 22. Said air headers 22—22 are connected by means of the air inlets 23 to the passageways 13—13 of the regenerators at the two 25 ends of the oven. The numerals 24—24 indicate 30 gas manifolds which through gas inlets 25—25 deliver combustible gas to the flues 7—7 underlying the sole or floor 1.

A baffle wall 26 is preferably mounted in each of the passageways 13—13, which baffle walls 35 extend from the medial wall 10 toward the ends of the oven. Said baffle walls 26—26 are disposed in parallel relationship with the horizontal wall 8 and are located between said horizontal wall 8 and the baffle walls 11—11. Said baffle 40 walls 26—26 stop short of the end walls of the oven. Members 27 may be provided adjacent to the end walls of the furnace, leaving apertures 28—28 in the baffle walls 26—26 spaced short 45 distances from the ends of the oven for admitting air from the regenerative chambers to the ends of the flues 7—7. The horizontal wall 8, which forms the lower boundary of the flues 7—7, is provided with a plurality of apertures 29—29 providing communication between the space above the baffle walls 26—26 and the flues 7—7. Slide bricks 30—30 have been illustrated 50 for modifying the extent of opening of the openings 9—9 and 29—29.

The numerals 31—34 indicate oil burners 55 which are adapted to be supplied with oil from

the oil headers 32-32 at the two ends of the oven and are adapted to be supplied with air and/or steam from the air headers 33-33 located at the two ends of the oven. Valves 32a-32a and 33a-33a control the supply of oil and air, respectively, to said burners 31-31. Said oil burners 31-31 communicate with the Venturi throats 34-34 disposed in a plane slightly above the plane of the members 27-27. Said burners 31-31 are preferably movable toward and away from the throats 34-34 for the purpose of controlling the amount of secondary air entering said throats. Disposed in position to receive the blast from the Venturi throats 34-34 are the refractory members 35-35. Flames and mixtures of atomized oil, steam, and/or air from the oil burners 31-31 are adapted to impinge against the members 35-35. It may be preferred to use a mixture of air and steam in the air headers 33; or it may be preferred to use steam alone in the headers 33 and admit all air at the secondary air inlets between the burners 31 and the Venturi throats 34.

The mode of operation of the above described embodiment of the present invention is substantially as follows: When it is preferred to use gas for combustion in the flues 7-7, gas will be alternately supplied through the gas inlets 25-25 at the two ends of the oven. When gas is supplied through the left-hand gas inlets 25, as the parts are viewed in the drawing, air will be supplied through the inlets 23 at the same end of the oven, which air in passing through the corresponding regenerative passageway 13 will be pre-heated for mixture with the gas being delivered from the gas inlets 25. At this time products of combustion from the flues 7-7 will pass through the right-hand regenerative passageway 13, heating up the structure defining said passageway, passing out through the right-hand tunnel 15.

Continuing with the example in which gas for combustion purposes is admitted at the left-hand end of the oven, the air for mixture with said gas, after passing through the corresponding regenerative passageway 13, will, in considerable proportions, pass through the aperture 9 at the left-hand end of the oven for uniting with the gas from the gas inlets 25 at the left-hand end of the oven. However, a material proportion of the gas from the left-hand regenerative passageway 13 will pass along above the partition wall 26 to the apertures 29-29 to unite with unburned portions of the gas delivered toward the mid region of the oven. The result is a relatively uniform heat distribution throughout the lengths of the flues 7-7. At the same time the products of combustion will in part pass downwardly through the apertures 29-29 at the right-hand end of the oven and the remainder of said waste heat gases will pass downwardly through the aperture 9 at the right-hand end of the oven. The result is the avoidance of excessive heat at the outer ends of said flues 7-7.

According to the present invention, oil firing may be substituted for the gas firing, or may be used simultaneously with the gas firing. When it is desired to use the oil burners 31-31, the injection of oil and steam and/or air is controlled by the valves 32a and 33a, and the amount of secondary air is controlled by the Venturi throats 34 and the locations of the burners 31 relative to said throats. With proper adjustments the members 35-35 may be heated to incandescence. With a surplus of oil delivered by the burners 31,

which oil is gasified on impingement against the corresponding member 35, the oil gas will pass through the corresponding openings 9 to the flues 7-7. Part of this oil gas will be burned at the corresponding opening 9, depending upon the amount of air admitted to said opening 9. The balance of the oil gas will be burned at the ports 29-29, according to the amount of air admitted at these ports, determined by the locations of the bricks 30-30. The term "surplus of oil" of course refers to an excess of oil over and above that necessary to combine with the air admitted through the oil burners.

According to the present invention, oil will be gasified and burned in the sole flues 7-7 in a manner similar to that discussed above in connection with gas admitted through the gas inlets 25-25, thus permitting the propagation of heat throughout the length of the flues and an even distribution of heat to the floor and the oven structure.

The advantages of the present invention will be apparent without detailed explanation. One advantage is that peak loads may be supplied by substituting oil for gas firing for short intervals, thereby eliminating large investments in gas storage holders. Another advantage is that coal tar oils produced in the carbonizing operation may be used for under firing, where the gas has greater economic value than the tar oils. Still another advantage is that petroleum oils can be used where their value is less than the gas produced in carbonizing. Another valuable advantage is that in starting up the carbonizing plant where gas is not available, oil can be used to heat the oven structure.

With reference to the advantage last mentioned, the following discussion may be had.

In starting up a new coking oven where a supply of gas has not yet been built up, a serious economic problem arises as to how to heat up the oven and get a supply of gas for commercial operation. In starting certain types of oven it has been common practice to build a producer plant or provide a blue-water gas producing plant for the purpose of supplying this gas for placing the plant in operation. This has required an investment of thousands of dollars in a commercial plant.

According to the present invention, ordinary salamanders fired with coke or other smokeless fuel are disposed along the regenerative faces of the ovens, and the products of combustion are led into regenerative chambers to heat up the brick work therein to a temperature of around 500 deg. F. Oil fittings are provided in connection with a few ovens, say about three ovens, and liquid oil is directed through these oil fittings toward the bricks 35-35. The stream of liquid oil will be ignited, whereby a flame will be directed against the bricks 35-35 to progressively heat said bricks. By reason of the impingement of the oil against the heated bricks, a certain amount of combustion will take place, resulting in the gasification of part of the oil. A further effect of the impingement is to break up the particles of oil to form soot, which will be carried along with the oil gas products into the combustion flues below the oven floor 4, air being provided for combustion purposes through the regenerative passages 13-13. After a few days' operation the oven is heated up to an operative temperature and in a short time the few ovens being started will be producing a supply of gas for operating purposes. After the first few ovens

have been started, the oil fittings may be transferred to another set of ovens and the same operation may be carried on, or the operation of the oil fittings may be supplemented by the gas being produced by the set of ovens which has already been started. After this second set of ovens has been put in operation the oil fittings may be transferred to still another set of ovens and will be utilized together with the gas that has been produced from the two sets of ovens first mentioned, and will heat up the third set of ovens. The operation is carried forward in like manner until the plant is in complete operation.

After the plant has been put in operation the oil fittings may be removed and transported to another plant, perhaps in an entirely different part of the country; or these oil fittings can be kept on hand so that in the event that the plant has ceased operations for any cause it can be easily started again, following the same procedure as described for the original start. In such event the investment in the oil fittings amounts to only a few hundred dollars as compared to many thousands of dollars. It will also be understood that the oil fittings may be kept in position at all times, so that in the event it is desirable to increase surplus gas from the coking plant, an oil or oil fuel may be used to carry on the carbonizing operation as a replacement for gas.

Though one embodiment of the present invention has been described in detail, many modifications will occur to those skilled in the art. It is intended to cover all such modifications that fall within the scope of the appended claims.

What is claimed is:

1. In a coke oven, in combination, a horizontal coking floor, means including a horizontal wall below said floor forming a plurality of heating flues extending longitudinally of said oven, means dividing the space below said horizontal wall into a pair of regenerative chambers, said horizontal wall having a plurality of apertures spaced lengthwise of said oven and providing communication between said flues and said regenerative chambers, certain of said apertures being located adjacent to the ends of said oven, means for admitting gas to said flues at the ends of said oven remote from said dividing means, means for admitting air to said regenerative chambers for mixture with said gas, oil burners at each end of said oven for delivering atomized oil to said flues, and refractory members located adjacent to the ends of said horizontal wall in front of said oil burners whereby said refractory members will be impinged by the blasts from said oil burners to cause gasification of the oil carried in said blasts.

2. In a coke oven, in combination, a horizontal coking floor, means including a horizontal wall below said floor forming a plurality of heating flues extending longitudinally of said oven, means dividing the space below said horizontal wall into a pair of regenerative chambers, said horizontal wall having a plurality of apertures spaced lengthwise of said oven and providing communication between said flues and said regenerative chambers, certain of said apertures being located adjacent to the ends of said oven, means for admitting gas to said flues at the ends of said oven remote from said dividing means, means for admitting air to said regenerative chambers for mixture with said gas, oil burners at each end of said oven for delivering atomized oil, and refractory members located adjacent to

the ends of said horizontal wall in front of said oil burners, whereby said refractory members will be impinged by the blasts from said oil burners to cause gasification of the oil carried by said blasts, each of said refractory members being located in position to cause the intermingling of the atomized oil in its corresponding blast with air from the corresponding regenerative chamber.

3. In a coke oven, in combination, a coking floor, said oven having longitudinal flues below said floor, the lower boundary of said flues being defined by a horizontal wall having apertures spaced therealong, certain of said apertures being located adjacent to the ends of said oven, said oven being provided with regenerative chambers below said wall and having communication with said flues through said apertures, gas burner means for directing gas to said flues for combustion purposes, oil burner means for delivering atomized oil, and refractory means located adjacent to the ends of said horizontal wall and adapted to be impinged by atomized oil from said oil burner means to cause gasification of said atomized oil.

4. In a coke oven, in combination, a coking floor, said oven having longitudinal flues below said floor, the lower boundary of said flues being defined by a horizontal wall having apertures spaced therealong, certain of said apertures being located adjacent to the ends of said oven, said oven being provided with regenerative chambers below said wall and having communication with said flues through said apertures, gas burner means for directing gas to said flues for combustion purposes, oil burner means for delivering atomized oil, and refractory means located adjacent to the ends of said horizontal wall positioned to be impinged by atomized oil from said oil burner means to cause the gasification of the oil delivered by said oil burner means and to promote the intermingling of oil from said oil burner means with air from said regenerative chambers.

5. In a coke oven, in combination, a coking floor, said oven having longitudinal flues below said floor, the lower boundary of said flues being defined by a horizontal wall having apertures spaced therealong, certain of said apertures being located adjacent to the ends of said oven, a pair of regenerative chambers having communication with said flues through said apertures, means for delivering gas at the two ends of said flues, means for delivering a mixture of oil and steam or air, and refractory means adapted to be impinged by the mixture from said mixture delivering means, said refractory means being located adjacent to the ends of said horizontal wall in front of said mixture delivering means whereby to be impinged by the blast from said mixture delivering means to cause the gasification of the oil carried in said blast and to aid in the intermingling of said mixture of oil and steam or air with the air from said regenerative chambers.

6. In a coke oven, in combination, a coking floor, said oven having longitudinal flues below said floor, the lower boundary of said flues being defined by a horizontal wall having apertures spaced therealong, certain of said apertures being located adjacent to the ends of said oven, said oven being provided with regenerative chambers below said wall and having communication with said flues through said apertures, gas burner means for directing gas to said flues for

combustion purposes, oil burner means, Venturi throat members for directing atomized oil from said oil burner means to said flues, and refractory means positioned to be impinged by the combustible mixture from said Venturi throat 5 means, said refractory means being located adjacent to the ends of said horizontal wall in

front of said oil burner means whereby to be impinged by the blast from said oil burner means to cause the gasification of the oil carried in said blast and to aid in the intermingling of the materials in said blast with air from said regenerative chambers.

MAURICE D. CURRAN.
